CASKET PLACER

James R. Brady, Marion, Ohio, assignor to The Marion Metal Products Company, Marion, Ohio, a corporation of Ohio

Application November 18, 1937, Serial No. 175,262

7 Claims. (Cl. 27—26)

This invention relates to casket placers and particularly to the combination with a casket lowering device, which may be of usual construction, of suitable members adapted to be supported by longitudinal elements of the casket lowering device or other suitable supports whereby to support a casket above an open grave during services and before persons attending a funeral have left.

10 To my knowledge it has occurred that when pallbearers were carrying a casket to its position above the open grave, the ground at the edge of the grave has given way with the result that a pallbearer has actually fallen into an open grave. 15 Accordingly, it is an object of my invention to render it unnecessary for the pallbearers to walk alongside the grave and to make it possible for them to bring the casket up to a point where one end projects slightly over an end of the open 20 grave and thereafter to slide the casket to final position.

The foregoing and other and more limited objects are realized in and through the device hereinafter described and illustrated in the accompanying drawings wherein Fig. 1 is a diagrammatic view showing the essentials of one type of casket lowering mechanism in place above an open grave together with a series of placers according to my invention resting on the 25 side bars of such lowering device; Fig. 2 is a side view of one of my casket placers showing the side bars of the casket lowering device in section, the remainder of such casket lowering device being omitted; Fig. 3 is a plan view of a 30 placer according to my invention; Fig. 4 is a section on the line 4—4 of Fig. 3; Fig. 5 is a section on the line 5—5 of Fig. 4; Fig. 6 is a longitudinal vertical section taken through a somewhat modified form of my invention and showing 35 means for braking the rollers to prevent motion of the casket in the event the casket lowering device might not be level or in the event an accidental push were given to the casket; Fig. 7 is a plan view of a modified form of the 40 invention incorporating braking means adapted to engage the casket to prevent motion thereof transverse to the axes of the rollers; Fig. 8 is a side view, partly in elevation and partly in section, of the device shown in plan in Fig. 7; Fig. 45 9 is a fragmentary section corresponding substantially to the line 9—9 of Fig. 7; Fig. 10 is a transverse section on the line 10—10 of Fig. 7; and Fig. 11 is a section corresponding substantially to the line 11—11 of Fig. 9.

50 Referring now to the drawings, the numerals

10 and 11 indicate respectively the longitudinal and transverse elements of a conventional casket lowering device. The bars 10 are supported in bearings 12 carried by and superposed upon the elements 11 and are rotatable in such bearings. Conventional means (not shown) are provided for preventing rotation of the elements 10 except when rotation thereof is desired and means for rotating such elements at a desired speed for lowering the casket. Flexible straps 13 are wound on the elements 10 so that by rotation of such elements they may be lengthened for lowering the casket into the grave or for supporting a vault base below the casket prior to lowering.

According to my invention, casket placers indicated generally by the numeral 14 are placed transversely of the elements 10 and rest thereon for supporting a casket independently of the straps 13. Each of the elements 14 is provided with notches 15 on its under surface, one at each end. These notches receive the elements 10, as indicated in Fig. 2 and are somewhat elongated so as to be useful with lowering devices having their longitudinal elements spaced at somewhat different distances. Between the notches 15 are anti-friction rollers 16 upon which the bottom of the casket is adapted to rest and along which such casket may be moved to a position over the grave, most of the weight being supported on the elements 14 and very little being transmitted to the earth at the side of the grave.

I prefer to make the placers 14 of channel beams and to mount the roller assemblies in openings in the web portion of the channel beam while forming the notches 15 in the flanges thereof. In order to prevent undesirable noise I prefer to line the notches 15 with rubber liners 17. The roller assemblies comprise plates 18 having central openings 19 and downturned ears 20 at the ends of such openings, such ears being preferably turned out from the metal within the outline of such openings. Said ears 20 are provided with openings 21 receiving trunnions 22 of the rollers 16. The plates 18 are preferably riveted, welded or otherwise secured to the web of the beam 14.

In Fig. 6, I have shown a slightly modified form of my invention which differs from the above described form in that I provide a brake for preventing motion of the rollers 16 after the casket has been placed in position. This brake comprises a cam segment 23 pivoted at 24 between the flanges of the channel beam 14. The roller engaging face 25 of the cam segment is eccen-

tric so as to lock as it is rotated clockwise and to unlock as it is rotated counter-clockwise. Also 5 pivoted between the flanges of the beam 14 is a foot lever 26 extending through an opening 27 in the web of the channel beam. A link 28 connects the lever 26 with the cam segment 23 whereby the device may be operated to lock the rollers 16 by stepping on the foot piece 29 of the lever 26 and may be unlocked by lifting such 10 lever. In Fig. 6 I have shown a second link 30 which it is to be understood connects with a second cam segment similar to that 23 and which cam segment operates on a second roller.

In Figs. 7 to 11 inclusive I have shown a modified form which is identical with the first described form except for the provision of a casket 15 engaging brake or holding means between the rollers in the case of one or more of the devices 20 rollers in the case of one or more of the devices to be used in a set. In this form a plate 31 is welded or otherwise secured to the edges of the 25 flanges of the channel member 14. Slidable upon the plate 31 is a channel member 32 provided with cam slots 33 in its flanges. Secured to the web portion of the channel 14 is a guide cylinder 34 registering with an opening 35 in such web. 30 The guide cylinder 34 is provided with vertical slots 36 adapted to receive the ends of a pin 37 carried by a casket engaging cylinder 38. Attached to the channel 32 is an operating element 39 extending to one end of the element 14 and provided with a hand grip 40.

In operation, the element 40 may be grasped and the element 32 moved to the right as seen in Fig. 9, resulting in elevation of the pin 37 and 35 consequently of the cylinder 38. Since the cylinder 38 is movable to a position above the upper surfaces of the rollers 16 it obviously may engage a casket to prevent motion thereof. If desired, the cam slot 33 may have such inclination that it 40 will remain locked until a disengaging force is applied through the element 39.

In practice I prefer to use one placer constructed as shown in Fig. 6 or as shown in Figs. 45 7 to 11 or provided with some equivalent braking means adapted to engage the roller or the casket 45 itself and to use two placers not provided with any braking means or equivalent, although it is to be understood that any desirable number of placers may be used and one or more thereof 50 may be provided with brakes or the like.

While I have shown and described the present 55 preferred embodiment of my invention, I wish it understood that I am not limited to the details of the disclosure but only in accordance with the appended claims.

Having thus described my invention, what I claim is:

1. In combination with a casket lowering apparatus having longitudinal elements adapted to extend alongside an open grave, a series of transverse supports adapted to rest on said longitudinal elements to support a casket, said transverse supports being provided with anti-friction means on their upper surfaces, and notches on their lower sides adapted to position them with respect to said longitudinal elements, said notches being elongated whereby to adapt the device for use with lowering devices having the longitudinal elements differently spaced, said notches being provided with deformable cushioning means adapted for engagement with said longitudinal elements.

2. In combination with a casket lowering apparatus having longitudinal elements adapted to

extend alongside an open grave, a series of transverse supports adapted to rest on said longitudinal elements to support a casket, said transverse supports being provided with anti-friction means on their upper surfaces, and notches on their lower sides adapted to position them with respect to said longitudinal elements, said notches being elongated whereby to adapt the device for use with lowering devices having the longitudinal elements differently spaced, said notches being provided with deformable cushioning means adapted for engagement with said longitudinal supports, said transverse elements comprising channel bars opening downwardly and said anti-friction means comprising rollers supported by 10 and projecting above the web portion of said channel bars.

3. In a device of the class described, as a sub-combination, a casket placer comprising a bar having elongated notches on one surface and 20 rollers rotatably mounted on the other surface, said rollers being placed between said notches and said notches being lined with deformable material.

4. In a device of the class described, as a sub-combination, a casket placer comprising a bar having notches on one surface and rollers rotatably mounted on the other surface, said rollers being placed between said notches and said notches being lined with deformable material, 30 said bar being channel shaped and having said notches formed in the flanges thereof and said rollers mounted partly in the channel and extending through openings in the web of the channel bar.

5. In the combination recited in claim 4, braking means mounted on said bar and movable upwardly thereabove to engage a casket resting on said rollers, and means accessible from an end of said bar for operating said braking means.

6. In combination with a casket lowering apparatus having longitudinal elements adapted to extend alongside an open grave, a series of transverse supports adapted to rest on said longitudinal elements to support a casket, said transverse supports being provided with anti-friction means on their upper surfaces, and notches on their lower sides adapted to position them with respect to said longitudinal elements, said transverse supports comprising channel bars 50 opening downwardly and said anti-friction means comprising rollers supported by and projecting above the web portion of said channel bars, and means associated with said channel bars for preventing motion of a casket resting 55 thereon transversely of the axes of said rollers.

7. In combination with a casket lowering apparatus having longitudinal elements adapted to extend alongside an open grave, a series of transverse supports adapted to rest on said longitudinal elements to support a casket, said transverse supports being provided with anti-friction means on their upper surfaces, and notches on their lower sides adapted to position them with respect to said longitudinal elements, said transverse supports comprising channel bars opening downwardly and said anti-friction means comprising rollers supported by and projecting above the web portion of said channel bars, movable means adapted to prevent rotation of one or 70 more of said rollers, and means for operating said last means to and from a position to lock said roller or rollers against rotation.

JAMES R. BRADY.
